US00D995031S

(12) **United States Design Patent** (10) **Patent No.:** **US D995,031 S**
(45) **Date of Patent:** **** Aug. 15, 2023**

(54) **ROOT VEGETABLE PRODUCT**

(71) Applicant: **McCain Foods Limited,**
Florenceville-Bristol (CA)

(72) Inventors: **Wei Zhang**, Shanghai (CN); **Hao Wang**, Harbin (CN); **Ling Wang**, Shanghai (CN)

(73) Assignee: **McCain Foods Limited,**
Florenceville-Bristol (CA)

(**) Term: **15 Years**

(21) Appl. No.: **29/801,139**

(22) Filed: **Jul. 27, 2021**

(51) LOC (14) Cl. **01-01**

(52) U.S. Cl.

USPC **D1/125**; D1/199

(57) **CLAIM**

We claim the ornamental design for a root vegetable product, as shown and described.

DESCRIPTION

FIG. 1 is a top perspective view of a root vegetable product in accordance with our Design;

FIG. 2 is a bottom perspective view thereof;

FIG. 3 is a top plan view thereof;

FIG. 4 is a bottom plan view thereof;

FIG. 5 is a front view thereof;

FIG. 6 is a right view thereof;

FIG. 7 is a rear side view thereof; and,

FIG. 8 is a left side view thereof.

1 Claim, 4 Drawing Sheets
